United States Patent Office

Des. 223,944
Patented June 20, 1972

223,944

TOY TRUCK CEMENT MIXER BODY

Theodore H. Zbikowski, Plymouth, and Lee J. Pfeilsticker,
Mound, Minn., assignors to Tonka Corporation, Mound,
Minn.

Filed May 14, 1971, Ser. No. 143,739

Term of patent 7 years

Int. Cl. D21—01

U.S. Cl. D34—15

FIG. 1

FIG. 2

FIG. 3

FIG. 4

FIG. 1 is a top plan view of the toy truck cement mixer body, showing our new design;

FIG. 2 is a right side elevational view thereof;

FIG. 3 is a rear elevational view thereof; and

FIG. 4 is a front elevational view thereof.

We claim:

The ornamental design for a toy truck cement mixer body, as shown.
